ALBERT TREFETHEN GOOKIN, OF CAMBRIDGE, MASSACHUSETTS.

RESILIENT WHEEL.

1,093,399.

Specification of Letters Patent. Patented Apr. 14, 1914.

Application filed October 26, 1911. Serial No. 656,818.

To all whom it may concern:

Be it known that I, ALBERT T. GOOKIN, a citizen of the United States, and a resident of Cambridge, in the county of Middlesex and State of Massachusetts, have invented a new and Improved Resilient Wheel, of which the following is a full, clear, and exact description.

My invention involves a new form of resilient wheel and the principal object of my invention is to provide an improved device of this class.

A further object of the invention is to provide a wheel made up of a hub and rim with a number of resilient spokes therebetween whereby when the wheel rolls over the ground the resiliency of the wheel will take up the shocks due to unevenness in the road.

Other objects and advantages of the invention will appear as the description thereof proceeds.

Reference is to be had to the accompanying drawings, forming a part of this specification, in which similar characters of reference denote corresponding parts in all the views, and in which—

Figure 1 is a side view of my improved wheel; Fig. 2 is a vertical sectional view of a fragment thereof; Fig. 3 is a vertical sectional view at right angles to the section of Fig. 2; Fig. 4 is a side view of the middle plate and one of the face plates in juxtaposed relation; Fig. 5 is a sectional view on the line 5—5 of Fig. 2; Fig. 6 is a sectional view through two of the spoke shanks adjacent the hub; Fig. 7 is a sectional view on the line 7—7 of Fig. 2; Fig. 8 is a perspective view of one of the fixed plates adjacent opposite ends of each spoke and which is adapted to hold an oil cup; Fig. 9 is a plan view of one of the dust guards positioned adjacent opposite ends of each spoke and showing a shank passing therethrough; Fig. 10 is a perspective view of one of the removable sections removed in order to show the construction thereof.

The wheel comprises a central hub designated as a whole by 1, together with a rim 2 and a plurality of telescoping resilient spokes 3, all of the parts being held together by suitable means to be presently described in detail.

The hub is made up of a plurality of parts comprising a central bearing portion for engagement with an axle, together with a number of plates or disks securely, yet re-

movably, held thereon. As shown particularly in Fig. 3 the hub comprises a middle plate 4 having face plates 5 on opposite sides thereof, each of the face plates being of a diameter equal to that of the middle plate; on opposite sides of the face plates 5 are the outer plates 6, one of which is preferably formed integral with the central cylindrical member 7, the other outer plate being provided with a central opening through which this member 7 passes, all of the parts being firmly secured in position by any suitable means, such as bolts and nuts 8. The member 7 is provided with a longitudinally extending bore 9 adapted to be positioned on an axle whereby the wheel may be supported.

Referring particularly to Fig. 4 it is to be noted that the middle plate 4 is provided with a plurality of radial pockets 10 equally spaced from each other and of peculiar conformation, each pocket being adapted to receive the spoke head and shank of each of the spokes when the parts are in assembled position, as shown particularly in Fig. 2. The middle section may be conveniently made up of a plate having a plurality of notches 11 around its periphery, together with a number of removable sections 12 having a reduced inner end 13, this inner end being adapted to lie adjacent the portions of the plate proper between the notches 11 in order to form circular pockets; all of the sections 12 are equally spaced apart and are secured in position between the face plates 5 by any suitable means, such as bolts and nuts 14. In Fig. 10 I have set forth one of these removable sections in perspective, it being shown provided with openings 15 for the passage of the bolts, and a longitudinally extending channel 16 having divergent inner ends 17 communicating with the inner ends of adjacent pockets 10.

Each of the spokes is intended to be telescopic in operation and to this end I have shown them made up in two sections, each section comprising a cylindrical spoke head 18 connected to the spoke end 19 through the medium of a suitable shank 20. Each of the spoke ends 19 offers a suitable support for a plurality of concentric tubes 21; the outer ends of the tubes of one section of the spoke being adapted to enter between tubes of the other section of the spoke whereby the spoke may be lengthened or shortened by drawing the sections longitudinally of each

other. Positioned between the tubes 21 are a plurality of helical springs 22, the outer ends of those in one of the sections being adapted to engage the outer ends of the tubes entering that section, all of which is shown particularly in Fig. 2 of the drawings. Each spoke head 18 and shank 20 is positioned in one of the pockets 10, shown in Fig. 4 and when all of the spokes have been thus positioned the second face plate 10 may be brought adjacent the middle plate and the parts secured together.

In order to provide for proper lubrication of the inner ends of the spoke heads and shanks I position an oil cup 23 in the outer end of each of the channels 16 in the removable sections 12 shown particularly in Fig. 2, the oil from each cup finding its way down the channel and through the diverging ends 17 thereof, where it comes in contact with the moving parts.

In order to prevent the entrance of dust and foreign matter into the pockets 10 wherein the spoke heads are positioned I provide dust guards 24, shown particularly in Fig. 9; each dust guard is preferably made up of a body portion 25 having a central opening 26 therein adapted to fit around the shanks 20, the opposite ends of the body portion being provided with recesses 27, the recesses of adjacent guards being adapted to receive one of the oil cups 23, as shown particularly in Fig. 6. These recesses 27 on adjacent dust guards, by registration with each other, permit relative movement of the parts or sliding of these plates when the wheel is in operation, there being a second fixed plate 28, shown particularly in Fig. 8, this plate being provided with a central opening 29 through which the oil cup 23 passes, the corners of the plate being provided with lugs 30 adapted to be bent around the dust guards 24 in order to keep these parts in position with respect to one another.

The outer end of each of the spokes is retained in engagement with the rim by retaining means somewhat similar to those carried by the hub, whereby the inner ends 50 of these spokes are retained in position. Referring particularly to Figs. 2 and 3, the rim is made up of a tire 31 and the rim proper 32, these parts being held together in any suitable manner, as by means of 55 threaded bolts 33. The retaining means comprises a middle plate 34 having a pocket 35 therein in which the cylindrical outer spoke head 18' and shank 20' are positioned, the pocket being formed by means of suitable sections 36 secured to the face plates 37 through any suitable means, such as bolts 38; the face plates being secured to the middle plate 34 preferably by bolts 39, the middle plate in turn being secured to the 60 rim proper 32 by means of bolts 40. The

outer end of the spoke is thus securely held in position, the inner end of the pocket 35 being shaped to fit the cylindrical end of the spoke and the diverging sides of the outer end of the pocket permitting movement of the spoke end within the pocket, in the plane in which the spoke lies. The thickness of the middle plate 4 is substantially that of the shank, thereby preventing lateral movement of the spokes. Each of the sections 36 is provided with a suitable bore or channel 41, see Fig. 2, there being an oil cup 23' secured in the outer end of the channel whereby lubrication of the spoke head in the pocket is assured; in order to prevent the entrance of dust and foreign matter into the pocket 35 I provide dust plates 24' adjacent each section 36, these plates being similar in construction to the dust plates 24 previously described, there being also a fixed plate similar to that shown in Fig. 8 already described. After the spokes have been positioned in the hub and secured therein, the outer ends of the spokes may be secured with respect to the middle plate 34 after which the tire 32 may be adjusted at the outer ends of the spokes and bolted in position thereon.

In the use of the wheel the different portions of the tire move relatively to the hub through the compression of the helical springs 22 contained within the spoke whereby the shock, due to unevenness of the road, is taken up by the spokes, the relative movement of the spokes to the hub and the rim being permitted by reason of the pocket construction, this construction also securing the spoke ends in position. If the tire or rim directly under a spoke comes into contact with a projecting portion of the road the spoke will be compressed an amount depending on the force of the shock, the tire coming back to original position after the obstruction has been passed over; should that portion of the tire which lies between 110 succeeding spokes be subjected to shock, the rim, by reason of its flexibility, will be deformed a certain amount, this deformation causing a limited movement of the spokes toward each other, the construction of the 115 pockets in the hub and the rim permitting this movement. The construction and arrangement of the parts is such that should any spoke become damaged from accident or wear, it may be easily removed and a new 120 one placed in position; the tire proper 31 may be of metal or rubber or any other suitable substance adapted to the purpose, the construction of the wheel itself forming a very efficient adjacent adjunct to a resilient tire.

The wheel may be made of different diameters adapting it for use on different vehicles, and the material of which the different parts is made may be chosen with a 130

view to rendering the wheel stronger or more efficient, such changes being largely matters of choice and comprehended within the appended claim.

5 Having thus described my invention, I claim as new, and desire to secure by Letters Patent:—

10 A wheel comprising a hub made up of a number of plates secured together and including a middle plate and face plates on opposite sides of the middle plate, the middle plate comprising a body plate of less diameter than the face-plates and having a plurality of notches around its periphery, and a plurality of removable outer sections arranged between the face plates and having reduced inner ends adapted to engage the portions of the 15 middle or body plate between the notches, the removable sections being spaced apart and forming with the body of the plate ra-

dial pockets, the inner ends of said pockets being circular and the outer ends of said pockets having diverging sides, a rim, a plurality of resilient spokes secured at one end to the 25 rim, the other end of each spoke comprising a head and a shank, the head being of greater diameter than the shank and rotatably engaged in the inner circular portion of one of said pockets of the hub, and 30 means for rigidly securing the removable sections to the face plates, whereby the heads are held in position in the said pockets and movement of the spokes relatively to the hub is permitted when the wheel is in use. 35

In testimony whereof I have signed my name to this specification in the presence of two subscribing witnesses.

ALBERT TREFETHEN GOOKIN.
